MEANS FOR FORMING BOLSTERS

Henrietta Lesko, Chicago, Ill.

Application April 25, 1950, Serial No. 157,974

4 Claims. (Cl. 5—340)

1

This invention relates to bolsters for enclosing pillows on the bed when the bed is made, and has for its principal object the provision of a new and improved device of this kind.

It is a main object of the invention to provide a device capable of being used as an independent unit to form a bolster for receiving the pillows as the bed is being made, and also capable of being attached to the bedspread to form a bolster in conjunction therewith.

Another object of the invention is to provide a bolster-forming device that can be maintained in clean and sanitary condition and which can be folded or rolled into a relatively small space when not in use as a bolster.

Another object of the invention is to provide a bolster-forming device that can be manufactured at low cost without sacrificing quality.

Further objects of the invention not specifically mentioned here will be apparent from the detailed description and claims which follow, reference being had to the accompanying drawings in which:

Fig. 1 is a fragmentary perspective view showing the bolster device in conjunction with a bedspread and bed;

Fig. 2 is a perspective view of the bolster-forming device;

Fig. 3 is a view similar to Fig. 1 and showing the bolster fastened to a bed; and

Fig. 4 is an end elevational view showing the bolster in secured together position.

It is a common practice, when making a bed, to fold and inner-fold the bedspread around the pillows so as to give to the bed when made a neat and attractive appearance. Such procedure makes it difficult to form a neat appearing bed since care must be taken to properly arrange the pillows and to fold the bedspread therearound.

In the prior art of which I am aware, numerous attempts have been made to facilitate forming neat appearing pillow-encasing bolsters. In certain instances fairly rigid tubular members have been provided, into which the pillows are stuffed and over which the bedspread is folded to form a generally cylindrical bolster extending substantially across the head of the bed. Such devices, while they make the task of performing a neat appearing made bed somewhat easier, are nevertheless subject to criticism in that the comparatively rigid bolster cannot readily be laundered and furthermore is difficult to store when the bed is in use.

The present invention provides a bolster-forming device consisting of a fabric member having

2

length sufficient to extend across or substantially across the bed. Along the longer sides of this member are fabric tubes formed either by folding the member over upon itself and stitching, or as separate tubular members secured to the edges of the fabric. Within the tubes are rod-like members composed of wood or the like, which are secured in the tubes in any preferred manner, such as by stitching. Attached to the tubes 10 are fastening devices arranged so that when the fabric is rolled around the pillows, and the two tubes brought in alongside of each other, the fastening devices can be engaged, one with the other, to fasten the bolster together. When it 15 is desired to launder the fabric, the rods are removed and the fabric can be washed and ironed in an ordinary manner. When the bed is in use, the bolster can be rolled or folded into rod-like configuration, occupying but little space and 20 small enough to be readily stored.

If desired, the bolster-forming device of the present invention can be attached to the bedspread by stitching or pinning, and loops attached thereto in position to cooperate with fastening 25 devices attached to the bed proper, thereby greatly facilitating making the bed. With such an arrangement, the spread and bolster are attached and aligned at the head of the bed by the fastening devices, the bolster is folded around the pillows and fastened, and the spread smoothed on the bed simply by pulling it towards the foot thereof and folding it over the foot end of the mattress. When it is desired to use the bed, the spread and bolster can be removed therefrom as 30 a unit and hung over the foot or otherwise stored, as desired.

Referring now to the drawings in more detail, particularly Fig. 2, it will be seen that the bolster consists of a fabric member 1, having length substantially equal to the width of the bed, and width substantially equal to the circumference of the pillows. The longitudinal edges of the member 1 are folded over upon themselves, as shown at 2, and stitched along one or more lines 35 3 to form loops or tunnels in which rod-like members 4 are disposed. If desired, one end of the tubes can be permanently stitched along the lines 5 to close that end, and the other end drawn together by stitches 6, best seen in Fig. 1.

Fixed to one of the tubular members 2 are fabric loops 13 which encircle fastening devices 14 which may conveniently be made of wood, fiber, plastic, or the like to secure device 14 in the loop. Fixed to the other tubular member 55 2 and in substantial alignment with the members

13, are loops 15, preferably also composed of fabric sewed to the tube. When it is desired to make the bed, the fabric is spread out as shown in Fig. 2, pillows laid thereon end to end and the fabric folded over the pillows to bring one of the tubular edges into registration with the other, and the fastening device 14 may then be extended through the loop 15 from one side and brought to bear against the opposite side to secure the bolster together, in the manner shown in Fig. 4.

As shown in Fig. 1, the fabric 1 is separate from the tubes 2 which are stitched thereto by seams 7. The fabric and tubes are secured to the bedspread 8 in any preferred manner, such as by sewing or pinning, the bedspread being folded along a line near the head of the bed and the fabric attached to the underside thereof.

One of the tubes extends beyond the fold, and secured thereto are additional loops 10 which encircle fastening devices 11 which are similar in construction to fastening devices 14. Attached to the mattress at the head of the bed are loops 12 which register with the fastening devices 11 as shown in Fig. 3 to secure the bolster and spread against movement lengthwise of the bed. The pillows are then placed on the bolster, which is wrapped around them and fastened by registering fastening devices 14 with the loops 15 as before, and the spread tidied over the bolster to complete the making of that end of the bed. The spread is smoothed out over the remainder of the bed by pulling towards the foot and folding the end of the spread over the mattress in the usual manner. Since the spread and bolster are fixed with respect to the mattress by fastening devices 11 and loops 12, the spread can be pulled taut without disturbing the arrangement at the head of the bed.

When it is desired to launder the bolster, the rods can be readily removed therefrom and the fabric washed in the usual manner. If desired, when the bolster is secured to the bedspread it can be removed therefrom for laundering, although ordinarily this will not be necessary since the bolster can be laundered with the spread equally well. When the bed is in use, the bolster and/or spread can be rolled or folded for convenient storage. Since the bolster is completely concealed, it can be made of relatively inexpensive material, such as muslin, and will have long life.

While I have chosen to illustrate my invention by showing and describing a preferred embodiment of it, I have done so by way of example only, as there are many modifications and adaptations

which can be made by one skilled in the art within the teachings of the invention.

Having thus complied with the statutes and shown and described a preferred embodiment of the invention, what I consider new and desire to have protected by Letters Patent is pointed out in the appended claims.

What is claimed is:

1. Means for forming a bolster for the pillows on a bed comprising: a rectangular piece of fabric; a fabric tube disposed at each side of said fabric; a rigid rod within each of said tubes; means securing said rods in said tubes; and fastening devices secured to one tube and projecting therefrom into engagement with cooperating fastening devices on the other tube.

2. A bolster-forming device comprising: a pair of fabric tubes; a fabric member extending between said tubes; fastening devices fixed to one of said tubes, each adapted to engage a cooperating fastening device on the other tube; and rigid rod-like members secured within said tubes.

3. Means for forming a bolster for the pillows on a bed comprising: a pair of spaced apart fabric tubes, disposed parallel to each other; a fabric member connecting together said tubes; fastening devices fixed to said tubes, each adapted to engage a cooperating device on the other tube to fasten the tubes together; and a rigid rod-like member secured within each tube and extending from end to end thereof.

4. Means for forming a bolster for the pillows on a bed comprising: a rectangular piece of fabric having length greater than its width; a hollow fabric tube extending along each of the longer sides of said fabric; fastening devices secured to said tubes, each arranged thereon to interengage with a cooperating device on the other tube when the fabric is wrapped around the pillows and the tubes thereby brought together; and a rigid rod-like member secured within each tube and extending from end to end thereof.

HENRIETTA LESKO.
